(57) **CLAIM**

The ornamental design for a vascular occlusion balloon as shown and described.

DESCRIPTION

FIG. 1 is a top and front perspective view of a vascular occlusion balloon in a partially-inflated state, in accordance with our new design, shown in an environment of use; FIG. 2 is another top and front perspective view of the vascular occlusion balloon; and,

FIG. 3 is a front elevational view of the vascular occlusion balloon, in another partially-inflated state.

The broken lines in the drawings illustrate portions of the vascular occlusion balloon that form no part of the claimed design. All other broken lines in FIG. 1 illustrate environment and also form no part of the claimed design.
